UNITED STATES PATENT OFFICE

2,508,204

APPARATUS FOR STRIPPING ARTICLES
FROM FORMS

John A. Weber and Edward A. Teck, Akron, Ohio,
assignors to The B. F. Goodrich Company, New
York, N. Y., a corporation of New York

Application February 27, 1947, Serial No. 731,276

6 Claims. (Cl. 18—2)

1

This invention relates to the stripping of articles from forms and is useful especially in stripping articles of stretchable material from the forms upon which they have been made.

In the production of flexible and elastic ink reservoirs for fountain pens, commonly known as pen sacs, the articles have been formed by deposit of rubber composition or other rubber-like material and have been vulcanized while on the forms. It has been found convenient to mount a plurality of forms on a holding bar for simultaneous manufacture. After vulcanization the articles require stripping from the forms.

Objects of the present invention are to provide effectively for stripping of the articles without manual effort, to provide for simultaneous stripping of a plurality of articles, to provide for assisting the removal by suction as well as fluid pressure, and to prevent over-inflation of the articles during the stripping operation.

These and other objects will appear from the following description and the accompanying drawings.

Of the drawings:

Fig. 1 is a front elevation of apparatus constructed in accordance with and embodying the invention, parts being broken away.

Fig. 2 is a sectional view thereof, taken on line 2—2 of Fig. 1.

Fig. 3 is a detail sectional view of the stripping instrumentalities and an article supported in stripping position.

Fig. 4 is a similar view with the article partially stripped from the form.

Referring to the drawings, the numeral 10 designates the frame of the apparatus which preferably has a pair of inclined top rails 11, 12 for supporting a bar 13 from which forms 14 are suspended. A shoulder 15 may be provided on the frame to locate the bar in stripping position. The forms 14 are arranged along the bar at regular intervals and each has an article 16 of rubber or other rubber-like material thereon which has been formed by deposit of material from a solution or dispersion thereof and has been vulcanized on the form.

For stripping the articles from the forms, a plurality of jet pipes 18, 19 are mounted on the frame and directed downwardly toward the mouth of the article and against the form. The jet pipes are preferably arranged opposite each other with two jet pipes directed at each form on the bar 13. All of the jet pipes are connected to manifolds 20, 21 which are in turn connected to a source of fluid pressure, such as a com-

2

pressed air supply 23, through a throttle valve 22. A foot operated lever 24 is connected to the valve arm 25 by a link 26 and may be depressed to open the valve against tension of a coil spring 27. The arrangement is such that an operator may depress the lever 24 and thereby discharge compressed air against all the forms simultaneously.

To prevent rupture of the articles by over-inflation due to ballooning of the articles under pressure of the air, and to assist in stripping the articles by the action of suction, a tubular member 30 is supported about each form coaxially thereof by the frame. The forms each extend substantially through a tubular member 30 with the mouth of the article on the form within the tubular member. The arrangement is such that the jet pipes 18, 19 simultaneously direct a blast of compressed air at the mouth of the article blowing into the mouth of the article. At the same time, excess air flows downwardly along the tube about the member, the article and the tube providing a reduced pressure about the article which tends to draw the article away from the form, as the air is entering the neck. Thus, this action of suction assists in moving the article from the form and opening it to receive the blast of air. Over-inflation is prevented by the confining walls of the tube, which nevertheless are lubricated by flow of air between the tube and the article with the result that the article is stripped from the form without tearing.

A container 31 is provided to catch the articles.

In use, a bar 13 of forms is placed in position on the frame and the operator depresses the lever 24 to release air under pressure. The articles are blown from their forms into the container.

Variations may be made without departing from the scope of the invention as it is defined by the following claims:

We claim:

1. Apparatus for stripping an elastic article from a form, said apparatus comprising a tubular member open at both ends, means for supporting a form with an article thereon within and in determinate fixed relation to the tubular member, and means mounted in determinate relation to said tubular member and in spaced-apart relation to the article on said form for directing a fluid under pressure into one end of the tubular member and against the mouth of

the article without contact of said fluid directing means with the article.

2. Apparatus for stripping an elastic article from a form, said apparatus comprising a tubular member open at both ends, means for supporting a form with an article thereon within and in determinate fixed relation to the tubular member, and a jet pipe mounted in determinate relation to said tubular member and in spaced-apart relation to the article on said form for directing air under pressure into one end of the tubular member and against the mouth of the article without contact of said jet pipe with the article.

3. Apparatus for stripping an elastic article from a form, said apparatus comprising a tubular member open at both ends, means for supporting a form with an article thereon within and in determinate fixed relation to the tubular member, and a plurality of jet pipes mounted in determinate relation to said tubular member and in spaced-apart relation to the article on said form to direct air under pressure from opposite sides of the article into one end of the tubular member and against the mouth of the article without contact of said jet pipes with the article.

4. Apparatus for stripping an elastic open-ended article from a form, said apparatus comprising means for supporting the form with the article thereon in a depending relation, a tubular member open at both ends positioned to surround the article in spaced relation thereto with the open end of the article within the tubular member, and jet pipes mounted in determinate relation to said tubular member and in spaced-apart relation to the article on said form to direct air under pressure downwardly into the upper end of said tubular member and against the open end of the article without contact of said jet pipes with the article.

5. Apparatus for stripping elastic open-ended articles from their forms, said apparatus com-

prising means for supporting a group of forms with articles thereon in depending relation, a series of tubular members open at both ends, each positioned to surround one of the articles in spaced relation thereto with the open end of the article within the tubular member, and jet pipes mounted at each tubular member in determinate relation to said tubular member and in spaced apart relation to the article therein to direct air under pressure downwardly into the upper end of said tubular member and against the open end of the article therein without contact of said jet pipes with the article.

6. Apparatus for simultaneously stripping a plurality of open-ended elastic articles from a plurality of forms mounted upon a carrier, said apparatus comprising means for supporting the carrier in determinate position, a series of tubular members open at both ends, each positioned in relation to the supporting means to surround one of the forms and the article thereon in spaced-apart non-contacting relation thereto with the open end of the article within the tubular member, and means mounted in determinate relation to said tubular members and in spaced-apart relation to the articles on the forms for directing fluid under pressure against the open ends of the articles without contact of said means with the articles.
